BUILDING UNIT

Horace G. Young, Ocean City, N. J., assignor, by
mesne assignments, to Katinka W. Young,
Ocean City, N. J.

Application December 20, 1929, Serial No. 415,568

1 Claim. (Cl. 72—36)

The present invention relates to an improved building unit, the purpose being to provide a unit to be supplied with a beautiful glossy surface, resembling polished granite, marble or the like, the glossy or glazed surface acting to render the unit damp and moisture-proof.

Another purpose is to provide a unit, together with a process for imparting to the face of the unit a highly polished surface, by constructing the unit of two consistencies of cement, the body of the unit being of a coarse cement, while that portion of the unit adjacent the polished surface may be constructed of a liquid consistency of cement, wherein the sand is finely pulverized, known as silica flour, so that when the unit is formed or molded, a glazed element is first inserted in the mold, so that when the unit is removed and allowed to set the required time, the glazed element can be removed from the unit, leaving the face of the unit polished or glazed.

Still another purpose is to provide any suitable glazed elements, such as glass, highly polished brass, copper or other polished metals, or any element which may be or can be given a polished surface may be used in the mold for imparting a polished or glazed face on the unit, or such metal as may be given a polished surface by the application of chromium.

It is well understood that the usual standard mold for making building units has its interior surface rough, hence the reason for using polished inserts. Furthermore though a mold may have its inner walls polished, such molds would be more or less expensive, and moreover when the unit is allowed to set in the mold, the air would not so easily enter between the inner faces of the mold and the unit, such as would enable the sides of the mold to be opened without defacing the surface of the unit. Such a method of imparting a polished surface to the unit may be used but such a method is not as practical, and furthermore considerably more expensive, than where glass inserts are used on the interior of the mold.

It is to be understood that the particulars herein given are in no way limitation, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a view showing the general outlines of a standard mold, showing the idea of

molding a unit with polished or glazed surfaces.

Figure 2 is a longitudinal sectional view on line 2—2 of Figure 1.

Figure 3 is a perspective view of the unit after it is removed from the mold, with the glazed insertions or elements attached to the unit, showing the unit in the process of setting or curing.

Figure 4 is a perspective view of the unit complete, the polished insertions or elements having been removed, the unit thoroughly set, a glazed or polished surface having been imparted to portions of the different faces of the unit.

Figure 5 is a view of a standard type of mold, showing an insert with its interior polished, so that the unit may be molded with polished faces.

Figure 6 is a longitudinal sectional view on line 6—6 of Figure 5.

Figure 7 is a detailed view with the rectangular insert removed.

Figure 8 is a detailed view of the unit constructed in the manner shown in Figures 5, 6 and 7.

Referring to the drawings, 1 identifies a mold of any standard type which may be suitable for this purpose, and wherein the sides and ends are capable of being opened, though they are not shown as opened, and 2, 3 and 4 identifies insert slabs or pieces of highly polished glass or other elements, which may be highly polished.

In the molding of the unit these slabs or insert elements highly polished are arranged adjacent the bottom, sides and ends 5, 6 and 7, the slabs being beveled on their edges as shown at 8, though not necessarily, so as to enable the slabs to fit together in position. After so arranging the slabs, with their polished faces 9 inwardly, sufficient semi-liquid cement consisting of finely pulverized sand, cement and water in a plastic condition is deposited in the mold, on the bottom slab and on the inner faces of the side and end slabs, as identified at 10. This semi-liquid cement, finely pulverized sand (better known as silica flour) and water with the addition of lime aggregates, and pigments in order to color as desired, when thoroughly set will receive on its outer faces highly polished or glazed finish, due to the glass or other slabs.

However, after applying this liquid cement, finely pulverized sand, water and the lime, the mold is filled with a courser cement to make up the body of the building unit, such cement being thoroughly tamped so as to adhere to the first deposit.

After the unit is so molded, the mold may be opened and the unit removed and allowed to set the required time, for example anywhere from ten to twelve to fifteen days. After the unit has thor-

oughly set, during which time air is allowed to enter between the slabs and the face of the unit (which enables the slabs to more or less loosen) the slabs are removed, thereby in this manner imparting to the face of the unit very highly polished finish.

Referring to Figures 5 to 8 inclusive it will be noted that a rectangular member 11 is inserted in the mold instead of the slabs. In other words 10 this rectangular member performs the same function as the slabs. The fact is the bottom of the member constitutes the bottom slab while the sides and ends of the member correspond to the insert slabs at the sides and ends in Figures 1 and 15 2, the only difference being that the corresponding parts are integral.

After the rectangular member is inserted in the mold the semi-liquid material is deposited in the mold against the inner face of the sides, ends and 20 bottom of the rectangular element, sufficiently to build up a face portion of the unit, said material being identified by the numeral 12. Subsequently to depositing the semi-liquid material in the 25 rectangular member, the mold is filled with the coarser cementitious material or concrete, so as to complete the body of the unit.

The inner surfaces of the sides and ends of the rectangular member are slightly inclined so as to permit this member to be more easily removed 30 from the unit after it is once set. This rectangu-

lar member may be made of glass, or any other material such as polished metal of any kind.

In either case when the unit is finally complete, it is provided with a polished face and polished sides and ends, there being a ridge or shoulder 12 along the sides and ends.

After the unit is thoroughly set the rectangular member may be removed or the slabs removed leaving the faces of the unit polished.

The invention having been set forth, what is 85 claimed is:

A building unit, comprising a unit body consisting of a major stratum constituting the larger portion of the unit, and composed of relatively coarse cementitious material, and a minor stratum extending over one entire face of the major stratum and substantially one half way down on two opposite sides and the two opposite ends, said minor stratum being composed of extremely fine grade of cementitious material, a simultaneously produced bonding between the two strata, the major stratum at points where the minor stratum terminates on the two sides and ends having a beveled shoulder, whereby when a number of units are used in a wall construction with the ends and sides of the major stratum in contact, the sides and ends of the minor stratum of the various units are spaced, said minor stratum on its face, sides, and ends having a highly smooth finish.
